UNITED STATES PATENT OFFICE

RODOLPHUS T. FIORINI, OF NEW YORK, N. Y.

STRINGED-INSTRUMENT HOLDER.

SPECIFICATION forming part of Letters Patent No. 361,817, dated April 26, 1897.

Application filed March 11, 1887. Serial No. 230,533. (No model.)

To all whom it may concern:

Be it known that I, RODOLPHUS T. FIORINI, of the city, county, and State of New York, have invented a new and Improved Stringed-Instrument Holder, of which the following is a specification, reference being had to the annexed drawings, forming a part thereof, in which—

Figure 1 is a plan view of my improved stringed-instrument holder, showing it in position in the violin-case. Fig. 2 is a side elevation of the holder detached from the case. Fig. 3 is a side elevation of a portion of a modified form of the device.

Similar letters of reference indicate corresponding parts in all the views.

The object of my invention is to provide a simple and efficient holder for holding the necks of stringed instruments—such as violins, guitars, &c.—in the instrument-cases; also upon music-stands used in orchestras, &c.

My invention consists in an internally-threaded socket adapted to be secured to the bottom of the instrument-case, and a standard fitted to the socket and provided with a fork adapted to receive the neck of the instrument, and furnished with a clamping device for holding the neck of the instrument firmly in the fork.

The socket A, of wood or other suitable material, is designed to be attached to the bottom of the instrument-case, as shown in Fig. 1, and is internally threaded to receive the standard B.

A fork, C, which is attached to or formed upon the upper end of the standard B, is fitted to the neck of the instrument in connection with which the holder is to be used, and is provided with a yielding lining, a, of chamois-skin, velvet, or other material. In one arm of the fork is formed a mortise, b, in which is pivoted an arm, D, which is capable of closing the opening of the fork, the said arm being provided with a yielding lining, c, of cork or analogous material, for engaging the strings and finger-board of the instrument.

The arm D is prolonged beyond its pivot d, and is connected with one end of an elastic band, E, the opposite end of the said band being connected with the fork C, near the bottom thereof. When the arm D is closed down

over the opening of the fork, it places the elastic band E under tension, and the said arm D is held in a closed position by a spring-catch, F, secured to the side of the fork C. When it is desired to release the neck of the instrument from the holder, the spring-catch F is pulled back, (as indicated in dotted lines,) and, the arm D being released, the elastic band E causes the arm to fly up in the direction indicated by the arrow, thus leaving the fork C open, so that the neck of the instrument may be readily removed from the holder.

My improved stringed-instrument holder prevents injury to the instrument while it is being carried, by holding it securely in its place in the instrument-case.

My improved stringed-instrument holder can be placed in any music-stand of any theater to keep the instrument perpendicular.

My improved stringed-instrument holder can also be used as a pipe-hanger, and in railroad-cars as an umbrella or cane holder.

Having thus fully described my invention, I claim as new and desire to secure by Letters Patent—

1. In a stringed-instrument holder, the combination of a standard or support having a fork adapted to receive the neck of the instrument, a pivoted arm arranged to close the fork and confine the neck of the instrument, and means for holding the said arm in a closed position, substantially as described.

2. The combination, with the standard B and fork C, of the arm D, pivoted to one arm of the fork and provided with the elastic opening-spring E, and the spring-catch F, adapted to hold the arm D in a closed position, substantially as described.

3. In a stringed-instrument holder, the combination of the internally-threaded socket A, the standard B, the fork C, provided with a yielding lining, a, the arm D, pivoted to the fork C and provided with a yielding lining, c, the elastic band E, adapted to raise the arm D, and the spring-catch F, arranged to hold the arm D in a closed position, substantially as described.

RODOLPHUS T. FIORINI.
